UNITED STATES PATENT OFFICE.

WILLIAM GIFFARD, OF SALFORD, ENGLAND.

CAR STARTER AND BRAKE.

SPECIFICATION forming part of Letters Patent No. 449,285, dated March 31, 1891.

Application filed August 28, 1890. Serial No. 363,284. (No model.)

To all whom it may concern:

Be it known that I, WILLIAM GIFFARD, engineer, a subject of the Queen of Great Britain and Ireland, and a resident of 23 New 5 Bailey Street, Salford, in the county of Lancaster, England, have invented certain new and useful Improvements in Arrangements and Mechanism for Stopping and Starting Tram-Cars, Omnibuses, and other Vehicles 10 running on Rails or Common Roads, of which the following is a full, clear, and exact description.

My improvements relate to stopping and starting apparatus applicable to tram-cars, 15 omnibuses, and other wheeled vehicles, and in which the momentum of the vehicle is stored in the act of stopping and utilized in starting or putting the carriage again in motion.

20 To render my invention perfectly clear, I will now proceed to describe the same in detail and with reference to the annexed four sheets of drawings.

In Sheet 1, Figure 1 is a side elevation of 25 the lower portion of a reversible tram-car, the bottom frame and axles being drawn in section so as to show my improved starter more clearly. Fig. 2 is a plan view of the bottom frame of the car and apparatus. In Sheet 2, 30 Fig. 3 is an enlarged sectional view of a portion of the lower framing of a tram-car having my invention applied thereto. Fig. 4 is a plan of a portion of Fig. 2. In Sheet 3, Fig. 3^a is a continuation of Fig. 3 on Sheet 2, 35 the line Y Y showing the point of disjunction. Fig. 5 is a view of Fig. 3 at the section-line A B. Figs. 6, 7, 8, and 9 are detail views which will be hereinafter more particularly referred to. In Sheet 4, Figs. 10, 11, and 12 40 are views of a modified arrangement of clutch and engaging-gear.

The apparatus consists of a helical spring *a* or series of springs inclosed in a cylindrical sheet-metal case *b*, the said case *b* being secured to blocks *c*, carried on the axles *d* of the car. The spring and case are thus suspended between the two axles. At each end of the case *b*, and fitting its interior loosely, 45 there is a piston-block *e*, with projecting bolts or studs *e'*, which project through slots *b'* in the side of the case *b*, as clearly shown at Fig. 5. The studs *e'* also pass through sliding

muffs *f*, of which there is one at each end of the case *b*, as shown at Figs. 1 and 2. The consequence of this arrangement is that if 55 one of the said muffs *f* is moved along the case *b* it carries with it the corresponding piston-block *e* and compresses the spring *a* against the piston-block at the opposite end of the case. I will now proceed to describe 60 how this compressing of the spring and consequent storing of power is utilized to stop and restart the car.

It will be observed on reference to Fig. 4 that each muff *f* carries two paws *f'* and *f''*. 65 An endless chain *g* engages with the paw *f'*, and a similar endless chain *h* engages with the paw *f''*. The chain *g* passes over chain-wheels *i*, mounted loosely on the axles *d*, and clutch-halves *i'* are formed in one with or secured to the chain-wheels *i*. The chain *h* passes over chain-wheels *j*, also mounted loosely on the axles *d* and similarly carrying clutch-halves *j'*. The chain *g* is the chain which at times forces one or other of the 70 muffs *f* along the case *b* and compresses the spring *a*, while the chain *h* is the chain through which the muff in being forced back by the spring transmits the power to the axles *d*, and so restarts the car. It will be observed in 75 Figs. 4 and 5 that opposite to the clutch-half *i'* there is another clutch-half *i''*, capable of sliding on the axle *d*, but forced to rotate therewith by means of a slip feather and groove *i''*. The clutch-half *i''* is slid in and 80 out of gear with the clutch-half *i'* by means of a clutch-fork *k*, suspended in a bracket from a pin *l*, and operated to and fro by means of a screwed stud *m*, the said screwed stud engaging with a threaded wheel-nut *n*, as clearly 85 shown at Fig. 5. The free end of the screwed stud *m* is supported in a bracket *o*, as shown, and slides to and fro therein. The nut-wheel *n* is toothed on its periphery and engages 90 with a sliding rack *p'*, forming the inner end 95 of the hook-bar *p*. The two hook-bars *p* (one at each end of the car) are kept in their proper normal position by means of a connecting-spring *p''*. Each hook-bar *p* engages at times 100 in the manner shown with a secondary hook-bar *q*, projecting beneath the driver's platform. This secondary hook-bar *q* is maintained in its proper position relatively to the hook-bar *p* by means of a spring *q'*, as clearly

shown in Figs. 1 and 3^a. The hook connections between the bars *p* and *q* are of course only necessary in the case of reversible or turnable cars. The hook-bars *p* are carried 5 on the bottom frame-work of the car. The bar *q* is carried by the reversible portion of the car, and on the car being rotated on its central pivot the hooked end of the bar *q* slips into gear with the corresponding hooks 10 on the bars *p* at either end. In a non-reversible car the hook connection may be dispensed with. The bars *q* *p* are pulled forward against the springs *q'* *p'* by the foot-lever *r* and connections, or it might be by a 15 hand-lever *r'*, as shown in dotted lines at Fig. 1. When the bars *q* *p*, and consequently the sliding rack *p'*, are pulled forward by the said foot or hand lever, the nut-wheel *n* is rotated by the rack and operates the screwed stud *m* 20 and fork *k*, so as to push the clutch-half *i'* in gear with the clutch-half *i*', and thus cause the clutch-half *i'* and the chain-wheel *i* to partake of the motion of the axle *d*.

It will be observed that on the outer side 25 of the paws *f'* thickened links or stop-blocks *s* appear, so as to prevent the chain from passing freely through the paws, except in one direction. For example, looking at Fig. 4, it 30 will be seen that if the chain *g* is pulled in the direction of the arrow it cannot slide through the paw *f'*, but must move the muff *f* in that direction. On the other hand, if the chain *g* were moved in a direction contrary to the arrow it would pass freely through the paw *f'*, and would, on the other hand, pull 35 forward the muff at the opposite end of the case *b* and which does not appear in the figure. The chain *g* thus acts only on the particular muff which it is requisite should be 40 slid along the case *b* to compress the spring. Similar thickened links or stops *s'* appear on the chain *h* to the outside of the paws *f''*, and as it is requisite to carry the chain *h* along 45 with the moving muff I provide means which are not shown on Figs. 1 and 2 to prevent confusion of the drawings, but which are shown separately in Figs. 6 and 7.

On each muff *f* I cast snugs *f''*, between 50 which I place a curved finger *t* exactly opposite the center of the chain *h*, which is indicated in dotted lines. On the stud *t'*, which carries the finger *t*, I also fix at right angles to the finger a lever *u*, carrying a bowl *u'*, which is opposite to the center of the case *b*. 55 I also provide a tappet-catch *v* projecting from the block *c*, the said tappet-catch being in the path of the bowl *u'*. Now it will be observed that when the muff *f* is at the end 60 of the case *b* the bowl *u'* is held up by the tappet-catch *v*, so that the finger *t* lies above the chain *h*, as in Fig. 6; but if the muff *f* should be pulled along the case *b* by the chain *g* (as when the car is being stopped) the bowl *u'* is moved clear of the tappet-catch *v* and 65 drops, thus allowing the finger *t* to fall into the opposite interstice of the chain, as in Fig. 7. The bowl meanwhile rolls along the

bottom side of the case *b* and keeps the finger in its depressed position, thus pulling the chain *h* along with it. When the muff 70 is thrust back again by the spring, (as, for example, when the car is being restarted,) the paw *f''* acts on the thickened links or stops *s'* and takes the chain *h* back with the muff. When the muff has reached the end 75 of the case, the bowl comes again in contact with the tappet-catch *v* and the parts resume the position shown in Fig. 5. As I have already said, the chain *h* is mounted on chain-wheels *j*, which run loosely on the axles *d*. 80 The clutch-half *j'* gears at times with the half *j*'. When the car is running, the clutch-half *j'* is not allowed to rotate, being in one piece with the stationary chain-wheel *j*. The clutch-half *j''* rotates with the axle *d*, and is capable 85 of sliding thereon with a slip feather and groove, as in the case of the clutch-half *i''*. As a consequence, when the car is being stopped and the clutch-halves are brought together by the means hereinafter described, 90 the clutch-half *j''* slips on the half *j'*, owing to the form of the teeth; but when the car is being restarted by the chain *h* driving the chain-wheel *j* and clutch-half *j'* the half *j'* 95 grips the half *j''* and drives it, thus rotating the axle *d* and starting the car. The chains *g* and *h* can be tightened or slackened, as desired, by means of the adjusting-screws *g'* and *h'*, which appear in Fig. 1.

The construction and arrangement of the 100 chief part of the mechanism having been thus explained I will now describe its operation.

Referring to Fig. 1, the car is of course run in the direction in which the driver looks— 105 viz., in the direction of the arrow. When it is desired to stop the car and store up the momentum as power for restarting, the driver operates the foot-lever *r* or hand-lever *r'*, so as to pull forward the sliding rack *p'* and rotate the nut-wheel *n*, thus throwing the clutch-half *i''* into gear with the clutch-half *i'*. The chain-wheel *i* now revolves, moving the chain *g* in the direction indicated in Figs. 1 and 2. The chain *g* pulls forward the muff *f* at the 110 farthest end of the case, the muff bringing with it the piston *e* and compressing the spring *a* in the case. This compression of the spring goes on until the car is stopped or the wheels are skidded. When the car is at a 115 stand, the parts are locked in position. The muff *f* in advancing brings with it the chain *h* by means of the paw *f''* and the traveling finger *t*, the action of which I have hereinbefore described. It will be observed that as 120 the paw *f'* is at the top of the muff and the paw *f''* beneath, the chains *g* and *h* are moved in contrary directions while the car is stopping. The movement of the chain *h* actuates the chain-wheels *j* and clutch-half *j'* in a direction contrary to the direction of rotation of the axles *d*, the clutch-halves *j'* and *j''* being then in slipping contact, the half *j''* having 125 been allowed to come against the half *j'* 130

by the means to be hereinafter described. When the car has stopped, the return-thrust of the compressed spring a on the muff f which has been advanced, and which would, if not counteracted, send the car backward, is resisted by the action of the chain h on the clutch-halves j' , which now bite the clutch-halves j^2 and tend to send the car forward. The forces of the chain g and the chain h being thus in equilibrium, the car remains stationary. When the car is to be restarted, the driver releases the foot or hand lever r or r' , which is immediately returned by the springs q' and p^2 , drawing the clutch-half j^2 out of gear. The equilibrium of force is thus upset. The muff being released from the hold of the clutch i' i^2 is caused to resile by the spring a pulling with it the lower stretch of the chain h , and turning the clutch-halves j' j^2 , so as to rotate the axle d in the proper direction to restart the car. The chain-wheel j , being of larger diameter than the chain-wheel i , gives greater leverage in starting the car. By the time the muff reaches the end of the case the car has been propelled for at least its own length, and the starting has been effected without calling for any effort on the part of the cattle. The car then proceeds on its journey, the clutch-halves i' i^2 remaining out of gear and also the halves j' j^2 .

I will now describe the means whereby the clutch-halves j^2 are put in and out of gear with the clutch-halves j' on these occasions only when the car is stopped and started. This apparatus is shown in the plan view, Fig. 2, but not on Fig. 1, in order to prevent confusion. Figs. 3, 4, and 5, on Sheets 2 and 3, also illustrate the arrangement. I cast or secure a bracket 10 on the block c . This bracket 10 carries a stud 11. The top of the stud carries loosely the lever 12. The central part of the stud carries a bell-crank lever 13. The longer arm of this bell-crank lever 13 constitutes a fork which engages with the clutch-half j^2 . A spring w tends always to push the clutch-half j^2 in gear; but the longer arm of the lever 12 rests against a stop 15, cast on the muff f . The outer ends of the levers 12 are connected to the inner arms of the bell-crank levers 13 by rods 16, the said rods crossing each other, as shown at Figs. 2 and 4. The consequence is that the lever 12 at one end of the case operates the bell-crank lever at the other end. To explain its action, and referring to Fig. 2, if the car when proceeding in the direction of the arrow is to be stopped the muff farthest from the driver is wound up, and the stop 15 being thus removed from the lever 12, the spring w on the front axle is free to push in the clutch-half j^2 . A rubbing contact takes place between the two clutch-halves owing to the ratchet shape of the teeth, and this lasts till the wheels are skidded or the car stopped. When the car is restarted, the revulsion of the muff drives the clutch-half j' , which grips the clutch-half j^2 , and turns the axle, and consequently starts the car. When

the muff has reached the end of the case, the stop 15 again acts on the lever 12 and pulls the clutch-half j^2 out of gear. The apparatus acts in the same manner at either end and according to the direction in which the car is traveling. The apparatus being made double, the car-starter will act in either direction, for when the car is slued round on its pivot the muff which was at rest during the operation just described will be brought into action when the car is making a return journey in the opposite direction. The hook portions q^2 p^3 are formed as shown, so as to engage automatically when the car-body is turned on its pivot, the part q^2 slipping out of gear with the part p^3 at one end of the car-framing and into gear with the corresponding part p^3 at the other end of the car-framing upon each occasion that the car-body is reversed—as, for example, at the end of a journey. When a non-reversible car is used, the hook connection is of course dispensed with and the mode of actuating the clutch-lever k could be greatly simplified.

The entire apparatus may be boxed in to preserve it from dust, dirt, and the weather.

It will be understood that I do not confine myself to the exact disposition or form of these parts or details of my invention, which can be obviously modified. I have pointed out a modification of a hand-lever r' which might be used instead of a foot-lever r , and it will, for example, be apparent that other modes than the described rack, nut-wheel, and screw might be used to throw the clutch-halves i' and i^2 into and out of gear, especially where the car-body is not pivoted to the under framing, as in the illustrated example. For example, I might use such an arrangement as I show at Fig. 8, where by simply depressing a fork 1, containing a grooved wheel 2, capable of embracing both halves i' and i^2 of the clutch, the two said halves can be brought together against the pressure of an interposed spring 3, which would disconnect the clutch-halves when the fork and grooved wheel were again raised. Further, to prevent possible overstraining and breakage by too sudden engagement of the clutch-halves i' i^2 I might modify the form, as in Fig. 9, making the chain half i' of the clutch with a frictional strap 4 on its periphery and having pins 5 on the revolving half i^2 . These pins would, when the halves are thrust together, engage with the lugs 6 on the strap 4, and if the shock or strain were excessive the frictional strap 4 would give way a little and so minimize the danger of breakage. An additional advantage of this arrangement would be that the engagement between the halves would be much more likely to be completely effected in all cases than in the case of a clutch having a number of teeth.

Figs. 10 and 11, Sheet 4, illustrate the application of a conical friction-clutch in conjunction with my invention. In this arrangement I also dispense with the sliding rack

and screw, which I have described with reference to Sheets 1 and 2 for the purpose of throwing the clutch-half i^2 in gear with the clutch-half i' . The sliding bar p is connected 5 to a bell-crank lever 17, which is carried on a stud 18 by a bracket 19, secured to the bottom frame-work of the car. The horizontal shorter arm of the bell-crank lever 17, which appears in perspective in the detached view, 10 Fig. 12, is connected by a link 20 to an arm of a forked bell-crank clutch-lever 21, pivoted in a fixed bracket 22. The fork of the lever 21 engages with the clutch-half i^2 , secured by slip feather and groove to the axle d . The 15 clutch-halves i', i^2 are formed conical in shape and the half i^2 drives the half i' by frictional contact when they are brought together by the fork. The action of the parts will be easily understood from the drawings. When 20 the bar p is pulled forward by the hand or foot lever shown in the preceding sheets, the bell-crank lever 17 pulls the link 20 downward and operates the clutch-lever 21, so as to move the clutch-half i^2 into frictional contact with the half i' . The chain-wheel i is thus rotated and the spring compressed in the manner already fully explained. When 25 it is desired to brake both of the car-axles at once, I connect the bell-crank lever 17 to one end of a double lever 23, pivoted about the center of the car by means of an adjustable connecting-rod 24. Another rod 25 connects the other end of the double lever 23 to the bell-crank lever at the other 30 side of the car. Thus both clutch-levers are operated simultaneously, and the retarding effect is exerted on both axles. The starting of the car may be similarly effected through both axles. To return the bell- 35 crank levers 17 to their normal position, I connect the longer arms to the respective ends of the double lever 23 by ties. (Indicated by the dotted line 26.) The said tie carries a spring 27, which is extended when 40 the bell-crank lever 17 is pulled forward. On the release of the hand or foot lever by the driver the springs 27 return the parts to the normal position shown in Fig. 10. In selecting a pivoted or reversible car to show in 45 combination with my invention I have purposely chosen a type of car in which most practical difficulties are to be met with and overcome.

Although I here specifically describe my

invention in connection with a tram-car, it 55 will be obvious that it is applicable to other types of wheeled vehicles.

I claim as my invention—

1. The improved apparatus for stopping and starting tram-cars, omnibuses, and other 60 wheeled vehicles, consisting of a spring a or series of springs confined in a case and acted upon by blocks or pistons e , connected to sliding muffs f , operated by endless chains passing over chain-pulleys, which operate 65 clutches capable of being manipulated by the driver or person in charge, so as to compress the spring or springs during the stopping of the vehicle and to utilize the power thus stored for restarting the vehicle, substantially 70 as hereinbefore described and illustrated.

2. In apparatus of the indicated nature, the spring a and case b , in combination with the sliding muffs f and chains g and h for the purposes, and arranged and acting substantially 75 as hereinbefore described and shown.

3. The means for throwing the clutch-halves i', i^2 into and out of gear, said means consisting of the combination of the foot-lever r or hand-lever r' and parts, the hook-bar q and 80 springs q' , the hook-bars p , racks p' , spring p^2 , nut-wheel n , screwed studs m , and fork k , arranged and acting substantially as described and shown.

4. The means for seizing the chain h and 85 moving it with the muffs f during the compression of the spring, said means consisting of the finger t , stud t' , lever u , and bowl u' , acting in concert with the tappet-catch v , with the objects, and substantially as described 90 and shown.

5. The means for throwing both front and rear clutches into gear simultaneously and thus retarding, stopping, and restarting the car through both axles, consisting of the 95 combination, with the movable parts of said clutches, of operating-levers engaging the same, the rod p , connections between the latter and one of said levers, a rod-and-lever mechanism connecting said clutch-operating 100 levers, and a spring and tie for restoring said levers to position, substantially as set forth.

In witness whereof I have hereunto set my hand in presence of two witnesses.

WILLIAM GIFFARD.

Witnesses:

DAVID FULTON,
JOSHUA ENTWISLE.
